UNITED STATES PATENT OFFICE.

GEORGE W. BROOKS, OF TOPEKA, KANSAS.

CHALK TROUGH FOR BLACKBOARDS.

Application filed May 3, 1923. Serial No. 636,409.

To all whom it may concern:

Be it known that I, GEORGE W. BROOKS, a citizen of the United States, residing at Topeka, in the county of Shawnee and State 5 of Kansas, have invented certain new and useful Improvements in Chalk Troughs for Blackboards, of which the following is a specification.

This invention relates to certain new and 10 useful improvements in blackboards, and more particularly pertains to the chalk trough and tray and the attaching means.

The present invention has for its objects among others to provide a simple and efficient yet durable trough which will effectually prevent the chalk dust from being scattered or blown away, the trough being also formed to prevent the chalk or crayons from rolling off, on to the floor.

It has for a further object to so construct 20 and arrange the parts that the attaching means for the trough shall form the means for supporting the tray beneath the trough. I so construct the trough that it can be cut 25 into desired lengths and secured in place economically without the necessity of holes or bolts, and that it can be easily cleaned, having no rough edges or uneven surfaces, having a hollow body and constructed to 30 allow of the necessary adjustments of the braces for locating them in any desired place. The braces serve the double purpose of fastening the trough and holding the blackboard in place on the wall or other 35 support. There are no projecting heads of screws or bolts to catch on the clothes of the persons using the blackboard and no countersinks or unsightly places in the face of the trough.

I provide corner blocks which will allow 40 the chalk trough to be fitted up into a corner or at right angles when desired. The corner blocks serve as receptacles for the chalk. The trough serves as a cover for the 45 tray and conceals the chalk dust. The trough is adapted for use with and attachment to any form of blackboard. It is practically indestructable and is sanitary and fire-proof.

Other objects and advantages of the invention will hereinafter appear and the novel features thereof will be specifically defined by the appended claims.

The invention, in its preferred form, is

clearly illustrated in the accompanying 55 drawings, which, with the numerals of reference marked thereon, form a part of this specification, and in which—

Figure 1 is a face view of a blackboard, with a portion broken away, showing my 60 chalk trough applied.

Figure 2 is a cross section of the same as on the line 2—2 of Figure 1, looking in the direction of the arrows.

Figure 3 is a view similar to Figure 1 65 with the chalk tray removed.

Figure 4 is a detail of the tray removed.

Figure 5 is a perspective view of the chalk tray removed.

Figure 6 is a section on the line 6—6 of 70 Figure 2, looking in the direction of the arrows.

Figure 7 is a section on the line 7—7 of Figure 8.

Figure 8 is a section on the line 8—8 of 75 Figures 1 and 7, looking in the direction of the arrows.

Figure 9 is an enlarged section on the line 9—9 of Figure 1, looking in the direction 80 of the arrows.

Figure 10 is a perspective detail of one of the attaching brackets.

Like numerals of reference indicate like parts throughout the several views.

Referring to the drawings— 85

1 designates a blackboard, which may be of any well known or approved form of construction, of metal, wood, or any composition.

It is preferably provided at the opposite 90 sides and at the top (the latter not being shown) with wooden moulding 2 covered by metal strips 3. This wood moulding serves to take up vibration and to act as a sound deadener. The covering of metal is for the purpose of making it more permanent and to reinforce the wood so that it will make a stronger and neater moulding and the metal can be finished with a coating of enamel before shipping. By this provision the device can be fitted up at the factory and applied wherever desired without any trouble or finishing.

The blackboard may be applied to the 105 surface of the wall and the chalk trough screwed to the wood grounds which are located in the walls of the building, and by friction will prevent the blackboard from

giving. In Figure 2 the wood grounds are indicated at 4 and the securing means at 5.

The chalk trough, as shown best in Figure 8, is formed of a single piece of material, metal, and shaped to form the oppositely inclined upper walls 6, the opposite vertical walls 7 and the inwardly extended walls 8 which in turn are bent to form the upstanding walls 9. The inclined walls 6 10 form a bottom for the trough which is tapered toward the centre as seen in Figure 8, and the space between the adjacent edges of these inclined walls is slotted as seen at 10, Figures 2 and 6, through which 15 slots the chalk dust will fall into the tray soon to be described. The trough member may be formed in length to be severed as occasion may require.

The chalk trough may be affixed in position by suitable means; in the present instance I have shown what has proven a very satisfactory means. 11 are brackets, one of which is seen clearly in Figure 10, and comprises the vertical body portion 12 having 25 the opening 13, forming the members 14 and 15, the latter being of greater length than the former and provided with an opening 16 for the reception of fastening means. This member 15 is provided at each end with an 30 angular slot 17 as seen clearly in Figure 10, for a purpose soon to be described. 18 is a member extending at a right angle from the vertical edge of the body portion and this is provided with one or more openings 19 for 35 the reception of screws or other securing means. This member 18 is omitted from Figure 8 for the sake of clearness.

In practice, three or more, depending upon the width of the blackboard, of these 40 brackets are employed, in the present instance, three; one at each end and one near the centre of the blackboard. They are applied by sliding endwise upon the chalk trough, the angular portions 8 and 9 of the 45 trough engaging in the angular slots 17 of the brackets as seen clearly in Figure 8. When in place the brackets are secured firmly in position by screws or the like 50 passed through the openings 16 and into the blackboard or the wall, and at the ends, by means of a screw or bolt or the like 20 passed through the hole 16 in the member 15 which 55 engages in the adjacent wall of a corner block soon to be described.

The corner block 21 has in one wall the opening 22 through which passes the bolt 20 as seen in Figure 9, and in adjacent wall 23 60 openings 24 through which pass the screws or the like 5 which secure the board to the wall or support. I employ one of these blocks at each end of the chalk trough as seen in Figures 1, 2, 3 and 6. The end of the chalk trough fits snugly against the adjacent end of a corner block to make a neat 65 joint, and the rear edge fits snugly against

the adjacent wall of the blackboard to make a neat joint at that point. The inner wall or end plate 25 of the end block forms a convenient means for cleaning the blackboard eraser by rubbing the latter over the edge 70 thereof.

Each corner block is cut away upon two adjacent sides as seen at 26 and 27 so that the blocks may be reversed, making the same 75 universal, for use at a corner or any other desired position.

These corner blocks form a convenient rest for the chalk, being flat upon their upper faces, and by being closed upon their 80 under sides as seen at 28 they form a convenient pocket in which the chalk may be stored if desired. The bottom 28 may be formed integral with the block, or it may be a separate piece as seen in Figure 7, flanged as at 29 and secured to the adjacent wall of 85 the corner block by bolts or the like 30.

In order to hold the braces or brackets 11 in place and prevent them from pulling out I fold or flange the ends of the flanges 9 of the trough as seen at 31 in Figure 9 and 90 bend them up against the ends of the member 15 of the brackets 11. This burr or bending of the parts causes the braces or brackets to stop about an eighth of an inch back from the chalk trough, which space allows room for a bracket 32, see Figure 7, the flange of which is held in place by soldering or by the bolt 30. This bracket or member 32 carries a thumb screw 33 which serves to 95 retain the chalk tray, soon to be described, in place. The end bracket braces have openings therethrough, through which bolts are placed to secure the end plates 32* in place. This end plate may also be used where 100 splices are made to break the joint.

34 is the tray for collecting the chalk dust. It is stamped up or otherwise formed from a single piece of metal, and comprises the sides 35 and 36 and the bottom 37, and from the bottom extends a downwardly directed flange 38 which is provided with an offset as at 39, the depending member 38 and the offset 39 forming a neat finish when the tray is 110 in position, as will be readily understood from Figures 1 and 8. The tray fits snugly between the inner end plates of the corner blocks to form a tight joint. It rests upon the brackets 32 as seen in Figures 5, 6, 7 and 8 and is secured against movement by means of the thumb screws 33, which permit of its 115 ready removal when it is desired to remove the chalk dust therefrom.

All the parts may be made of galvanized iron, or any other suitable material all of 120 which may be finished with an enamel surface. Whatever the material used it will give the same results and will make a sanitary article.

Referring to Figure 8 it will be seen that 125 the chalk trough forms a cover for the chalk 130

dust tray, not only concealing the dust but preventing the same from being scattered or blown around.

The trough being of springy material will insure a close fitting to the blackboard.

Modifications in detail may be resorted to without departing from the spirit of the invention or sacrificing any of its advantages.

What is claimed as new is:—

- 10 1. A chalk trough having imperforate inclined walls and a perforated bottom, and side walls having inturned and upturned portions, brackets, and corner blocks cooperating with said brackets and with said portions.
- 15 2. A chalk trough having imperforate inclined walls and a perforated bottom, and side walls having inturned and upturned portions, brackets, corner blocks cooperating with said brackets and with said portions, and a tray supported from said portions.
- 20 3. A chalk trough having imperforate inclined side walls and a perforated bottom, corner blocks adjacent the terminals of said trough, brackets connecting said trough and blocks, and a tray fitted snugly between the inner walls of the corner blocks and supported by said brackets in position underlying said perforated bottom.
- 25 4. A chalk trough having a body portion with oppositely inclined imperforate walls and a perforated bottom, and tray-supporting means having interlocking connection with said trough and having means on which the tray rests.
- 30 5. An attaching bracket for the purpose described embodying members at substantially right angles to each other, one of said members having slots one of which is angular, the said member having an open-ended passage, and a tray-supporting member extending from said passage at substantially right angles to said member.
- 35 6. A chalk trough having depending sides with angled portions, and brackets having

slots cooperating with said angled portions to connect said trough and brackets.

7. A chalk trough, a tray disposed beneath the same, and interposed means having interlocking connection with the trough for supporting the tray.

8. A chalk trough having its side walls formed with angled portions, and corner blocks, each cut away upon two adjacent sides to adapt it for use at either end of the trough.

9. A chalk trough having its side walls formed with angled portions, and corner blocks, each cut away upon two adjacent sides to adapt it for use at either end of the trough, and brackets for use at the corners at the ends of the trough and formed with longitudinal portions to support a tray.

10. A chalk trough having depending angular portions, and a bracket having angular slots for cooperation with said angular portions and having means for supporting a tray beneath the trough.

11. A supporting bracket for use with a chalk trough and tray, the same comprising a body portion with an arm having angular slots at the ends, and a right angled member having openings whereby it may be secured in place.

12. A supporting bracket for use with a chalk trough and tray, the same comprising a body portion with an arm with angular slots at the ends, a right angled portion whereby it may be secured in place, and a lateral member for supporting a tray.

13. A supporting bracket for use with a chalk trough and tray, the same comprising a body portion with opening and angular slots at the ends, a right angled portion for securing it in place, a lateral member extending from said opening, and means in the last named member for securing a tray in place thereon.

In testimony whereof I affix my signature.
GEORGE W. BROOKS.
